(57) **CLAIM**

The ornamental design for a modular rifle, as shown and described.

DESCRIPTION

FIG. 1 is a front perspective view of a modular rifle showing my new design;

FIG. 2 is a first side view thereof;

FIG. 3 is a second side view thereof;

FIG. 4 is a bottom view thereof;

FIG. 5 is a top view thereof;

FIG. 6 is a front view thereof; and,

FIG. 7 is a back view thereof.

Any broken lines within this Figure showing the environment is for illustrative purposes only and forms no part of the claimed design.
